UNITED STATES PATENT OFFICE.

LOUIS BERTRAM COUSANS, OF LONDON, ENGLAND.

CASING FOR CENTRIFUGAL FANS AND PUMPS.

1,019,762.

Specification of Letters Patent. Patented Mar. 12, 1912.

Application filed December 3, 1910. Serial No. 595,437.

To all whom it may concern:

Be it known that I, LOUIS BERTRAM COUSANS, of Effingham House, Arundel street, London, England, engineer, have invented 5 certain new and useful Improvements in and Relating to Casings for Centrifugal Fans and Pumps, of which the following is a specification.

This invention relates to centrifugal fans 10 and has for its object to provide an improved construction of fan casing and pedestal.

The improved fan casing is constructed 15 of sheet metal and I attach the edges or periphery to the sides by making a series of small slots in the sides and forming projecting tags on the edges or vice versa, the tags passing through the slots and being turned over after insertion, the joints in the 20 corners being stiffened with strips of wood or analogous material bent or straight according to the shape of the case, these being nailed or screwed into position through the sides and edges of the case. Where the pressures 25 generated by the runner are low I may discard the slots and tags and rely wholly on the wood strips nailed or screwed into the corners for support. Outlets may be formed in the side or edges of the case.

30 Figure 1 is a perspective view of one construction of the improved fan casing and support therefor; Figs. 2 and 3 are respectively sectional plan and side elevation of Fig. 1; and Figs. 4, 5, 6, 7 and 8 show details of construction.

Similar letters refer to similar parts in the drawings.

In the illustrated construction the fan casing is formed of sheet metal, the sides *g* 40 being attached to the peripheral or connecting part *h* by making a series of small slots *i* (Fig. 6) on one part and forming projecting tags *j* on the other part, the tags being passed through the slots and turned 45 over after insertion as shown in Fig. 17. The joints in the angles are stiffened with strips of wood *k* or analogous material shown in Fig. 2, the said wooden strips being bent or straight according to the shape 50 of the fan casing, and are nailed or screwed in position through the sides of the case as shown in Figs. 5 and 8.

Where the pressures generated by the fan

runner are low I may discard the slots and tags and rely wholly on the wood strips *k* 55 nailed or screwed into the corners for support (see Fig. 5) and the required outlets are formed in the sides or edges of the case. To improve the appearance, one edge may be beaded over as at *h'*.

In Figs. 1 to 3 each side of the casing *b* 60 consists of four separate pieces of sheet metal *m'* *m²* *m³* *m⁴* suitably shaped and adapted to be assembled to form a complete side by being nailed or otherwise secured 65 along the adjacent vertical edges *o* *o* to vertical wood bars or battens *p* *p*. The fan casing when assembled is supported by attaching the said vertical wood bars *p* *p* to the vertical members *q* *q* of an angle iron 70 framework adapted to form on one side of the casing an extended platform *Q* for carrying the motor. The vertical members *q* *q* are as shown extended above the platform 75 to the height of the wood bars *p* *p*, and the upper ends of the said members *q* *q* may if desired be braced to the platform by struts or stays such as *r* to secure rigidity. In some cases the struts *r* may be disposed as shown in dotted lines.

80 What I claim and desire to secure by Letters Patent is:—

1. A fan casing consisting of a body comprising side plates and a peripheral plate, one of said side plates being made in sections, wooden battens positioned outside of 85 said casing for joining said sections together and a bracket for carrying a motor, said bracket comprising angle irons supporting said battens.

90 2. A fan casing consisting of a body comprising side plates and a peripheral plate, both of said side plates being made in sections, wooden battens positioned outside of 95 said casing at each side thereof for joining said sections together and a bracket for carrying a motor, said bracket comprising angle irons adjacent both sides of the casing for supporting said battens.

In witness whereof, I have hereunto 100 signed my name in the presence of two subscribing witnesses.

LOUIS BERTRAM COUSANS.
